METHOD OF MAKING CENTRIFUGAL PUMPS

Martin B. MacNeill, San Francisco, Calif., assignor to Fairbanks, Morse & Co., Chicago, Ill., a corporation of Illinois

Application January 9, 1933, Serial No. 650,776

6 Claims. (Cl. 29—156.8)

This invention relates to improvements in centrifugal pumps and method of making same, and more particularly to an improved form of impeller for a small, high speed centrifugal pump 5 intended for use in home water systems, and the like.

Heretofore the pumps generally employed to supply water under pressure to home water systems have been of the more usual reciprocating 10 types, which generally require considerable mounting space. However, centrifugal pumps have been tried, but with little operating success, because of the enormous capacity of even a small pump, operating at an economically high speed; 15 and where such pumps have been made to deliver a moderate quantity of water, sufficient for domestic requirements, the accomplishment has been at the expense of economical pump speeds, and, consequently, efficient pump operation. It is, 20 therefore, an object of the present invention to provide a centrifugal pump impeller and method of forming same, such as to obviate the difficulties above noted.

Another object is attained in an improved centrifugal pump of a particularly rugged build, having few parts, of uniform and easily interchangeable construction, which may be readily incorporated in a simple domestic water supply system.

30 A further object is attained in an improved impeller member for a small centrifugal pump, which is constructed of a single piece and adapted to deliver a sufficiently small quantity of water, at an economical and efficient speed of operation, 35 to adapt it for home use.

A still further object is attained in an improved centrifugal pump which is particularly economical in its operation and manufacturing cost, especially as compared with pumps of other principal types, of similar capacity, and which requires only a small mounting space.

40 Yet another object of the invention is attained in an improved centrifugal pump impeller of high speed type, characterized by a low discharge rate, such that the peak torque requirements are minimized, requiring a connected prime mover, such as a motor, of lower power rating than is necessitated with a reciprocating pump to supply a system of comparable per diem water capacity.

45 Further objects and advantages will appear from the following description, and from the drawing, in which:

Fig. 1 is a sectional elevation of a preferred form 50 of centrifugal pump, as taken along line 1—1 in Fig. 2; Fig. 2 is a sectional elevation of the pump,

as taken along line 2—2 in Fig. 1, and Fig. 3 is a lateral sectional elevation of a pump impeller during an intermediate stage of production.

Referring now to the drawing by numerals of reference, 10 designates generally, a centrifugal pump containing present improvements which will appear as the description proceeds. As shown in Fig. 1, the pump casing is preferably composed of two sections 12 and 14, section 12 including a webbed base bracket or securing member 16, which, as preferred in the present disclosure, is formed integrally with the section, and an extended tubular portion 18, which is provided as a bearing for a pump impeller shaft 20. A stuffing box 19 may be provided adjacent the outer end of the tubular portion 18 to prevent leakage along the shaft. The base bracket may be held on a suitable base 22 by any preferred means, such as bolts 24. Ribs, or web members 26 are provided, preferably integrally with the pump case section 12, as a means for strengthening the pump assembly. A shouldered seat portion 28, on the periphery of the section 12, receives, in assembly thereon, a peripheral shoulder portion 30 of section 14, the sections being secured together by bolts 31, or by any other suitable means. An extended inlet fitting 32 is preferably formed integrally with the section 14, centrally thereof, and is threaded internally at 34 to receive one end of an inlet pipe 35. A pump volute 36, of usual form, is provided in the peripheral portion of the section 14, and is provided at its outlet end with an outlet pipe fitting or connection 37, (Fig. 2).

35 A novel pump runner or impeller 38, rotatably disposed within the casing formed by the sections 12 and 14, is preferably formed of a single piece of material, such as copper or brass, in the shape of a plate or disc of suitable thickness, as illustrated in Figs. 1 and 2. The impeller is provided with an extended hub portion 40, on one side thereof, which, in the present example, is preferably made integrally with the disc, for securing it to one end of the shaft 20, as by a threaded connection. Since the impeller is intended, in operation, to rotate at a relatively high speed, variable according to the size and diameter of impeller, the threaded shaft connection may be made more secure by any of the well known means for accomplishing that result, for example, such as rusting the connection, or providing a lock pin 41 through the hub and shaft. The impeller member is provided with an extended portion 42 on the side opposite the hub 40, and has formed therein an inlet chamber 44, or eye, in line and substantial register with the inlet con-

nection 35. As preferred, the impeller inlet portion 42 may be positioned and partly bearinged on a wear or bearing ring 46, seated against an internal shoulder 47, in a portion of the section 14 5 adjacent the portion 32. Such a bearing, placed as shown in Fig. 1, will materially aid in decreasing vibration of the impeller resulting from high speed operation.

One or more centrifugal, thread-like passages 10 48 are formed in the impeller 38, to conduct water from the inlet chamber 44 to the volute portion 36 of the casing, the peripheral openings of the 15 passages being positioned so as to direct the water flow into the volute, substantially as shown in Fig. 1. The passages may be of uniform transverse section, as illustrated, or they may be of a slight conical trend. It will be readily understood that the number and diameter of passages in the impeller is to be determined by the desired quantity 20 of water to be delivered to the water system. In Fig. 2 of the present example, four such passages are shown, each passage being curved in form, extending substantially radially and having their inner ends tangential to the eye 44, more 25 particularly in Fig. 2, tangential to the circumferential wall surface of the inlet chamber. Further, the diameter of the passages may be chosen, within the limits of the particular impeller size and thickness, and is to be governed according 30 to the quantity of water to be delivered, and number of passages employed. The impeller passages may be given the predetermined degree of curvature as by drilling or coring the passages radially, or slightly offset from the radii, and tangentially 35 to the eye 44 after the impeller body is cast or otherwise initially formed. The desired curvature is then imparted by gripping the impeller disc rim in a suitable clamp, the disc then being heated, and the axial portions twisted in the 40 proper direction and to the angular extent to attain the desired curvature of the passages. Fig. 3 illustrates an example of an impeller body prior to its treatment for curving the passages.

The presently noted improvements in the form 45 and construction of an impeller for a small, high speed, centrifugal pump, which adapt the pump for economical use in a water supply system of low capacity and requirement, presents a decided advantage in manufacture, over those pumps 50 of other types heretofore employed for the same or a similar purpose. The pump impeller, disclosed in detail hereinabove, is so constructed as to eliminate difficulties which have heretofore rendered the very small sizes of centrifugal pumps 55 impracticable, inefficient, and often times impossible of installation.

It is to be understood, of course, that the present specific disclosure of preferred and modified forms of my invention, in no way limits the invention, and that further modifications may be

made without departing from the full intended scope of the invention, as defined in the appended claims.

I claim:

1. The herein described method of constructing a pump impeller which consists in forming a substantially solid disc-like body, in recessing an axial portion of the body to constitute an impeller inlet chamber or eye, in clearing the metal internally of the body to a uniform extent along each of a plurality of spaced lines from the periphery of the body to the eye, whereby to define a plurality of thread-like passages between the eye and the periphery of the impeller body, and in relatively displacing the peripheral and axial 15 parts of the body to shape the said passages.

2. The herein described method of forming a cast centrifugal pump impeller, which consists in axially recessing a substantially solid disc-like element, in forming impeller passages in the element between its periphery and its axial portion, and in shaping the passages by twisting the element following casting thereof. 20

3. The herein described method of constructing an impeller for a high speed centrifugal pump, which consists in forming the impeller body as a solid element between an eye portion and the periphery, in forming a plurality of passages extending from the periphery, through the solid portion of the body and into the eye portion, and in 30 shaping the passages by angularly displacing a part of the solid body element.

4. The herein described method of forming an impeller for a centrifugal pump, which consists, in forming an impeller body as a substantially 35 solid plate having a central recess, in forming openings in said plate from the periphery thereof to said recess to form a plurality of passages tangentially of the recess, and in subjecting said body to a twisting action to determine the course of 40 said passages.

5. The herein described method of forming a centrifugal pump impeller, which consists in drilling a substantially solid plate-like body from a plurality of points toward the periphery to form a plurality of passages of substantially uniform transverse section, in recessing the axial portion of the plate-like body to interconnect the inner ends of said passages, and in angularly displacing the peripheral and axial portions of the body while 50 heated, to determine the trend of the passages. 45

6. The herein described method of forming a centrifugal pump impeller which consists in drilling a substantially solid circular plate-like element from a plurality of points on its periphery, toward its axis to form passages of a general radial trend, and angularly displacing the peripheral and axial portions of the body to impart a curvature to the drilled passages. 55
